UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,170,978.

Specification of Letters Patent.

Patented Feb. 8, 1916.

Application filed May 5, 1913. Serial No. 765,719.

To all whom it may concern:

Be it known that I, ALFRED G. F. KUROWSKI, a citizen of the United States, residing in Brooklyn borough, in the county of Kings, city and State of New York, have 5 invented certain new and useful Improvements in Type-Writing Machines, of which the following is a specification.

My invention relates to attachments for platens of typewriting machines, and more 10 particularly to a holder adapted to be applied to a rotary platen for holding cards, address-stencils and the like.

An object of the invention is to provide a 15 suitable holder for stiff cards or for stencil blanks adapted to be stenciled for use in connection with an addressograph; such stencils usually being provided with a border of stiff cardboard.

The holder consists of two members 20 formed to surround the platen and connected by a hinge extending lengthwise of the holder and platen. The free edge of one of said members is formed into a bearing for a longitudinally 25 slideable locking bar carrying pins adapted to enter inclined or cam slots formed in the free edge of the other member. When the pins are in position in the slots, the locking bar is moved longitudinally to 30 cam the two members of the holder together and clamp it on the platen. The holder is provided with curved guides to receive a card or stencil blank.

Other features and advantages of the 35 invention will hereinafter appear.

In the accompanying drawings, Figure 1 40 illustrates my invention applied to the platen of an Underwood typewriting machine. Fig. 2 is a perspective view of the holder detached from the platen. Figs. 3 and 4 are detail 45 views of the clamping device for the holder, and showing the latter respectively in released and clamped position. Fig. 5 is a sectional end elevation view of the holder and also shows a stencil blank partially inserted into the holder.

The roller platen 1 is secured to an axle 50 2, journaled in the ends of a platen frame 3. Secured to the platen axle are thumb wheels 4 and 5, and a line-space wheel 6 adapted to be operated by the usual line-space mechanism. The work holder comprises members 55 8 and 7 forming, respectively, a holder portion and a clasp or keeper portion therefor, both curved to conform to the surface of

the platen and connected by a hinge 9. The free edge of the member 7 provides a socket or guideway in which is slideable a locking bar 10 extending longitudinally of the holder, and having its ends 11 bent upward to form thumb pieces. The guideway for this bar may be formed by bending the free edge 12 of the member 7 back upon itself. Secured to the bar 10 are locking pins 13 60 adapted to enter or project through inclined slots 14 in the free edge of the member 8. When the locking bar 10 is moved to the left, as shown in Figs. 2 and 3, the holder may be placed on the platen and the pins 13 extended through the slots 14 and the locking bar moved to the right to cam the two members of the holder together, thereby clamping them to the platen. 65

Fig. 4 indicates the holder and locking bar in clamped position. The pins 13 may be headed if desired to prevent accidental separation from the slots 14. The holder is provided with guides 15 to receive the card or stencil which is to be written upon. Each of these guides may be in the form of a plate 70 connected by rivets 16 to the holder, or otherwise secured; said plates each having an offset or raised portion to provide a space or groove 17 to receive the edge of the work-sheet or card. The end of the guide may be in the form of an outwardly 75 curved lip 18, to permit the ready insertion of the card. Between the guides 15, the holder is cut-away or formed with an open space 19, exposing the area of the card 80 which is adapted to be written upon. 85

In Fig. 5 is shown a stencil card or blank 90 comprising a body 20 of thin sheet material suitable for being stenciled, and a border 21 of heavier material such as cardboard. This stencil is shown partly inserted in the holder. When fully inserted, the lower edge of the stencil or card may rest against the hinge 9 which forms a stop therefor. In this position the stencil covers the opening 95 19, so that an address or other legend may be stenciled thereon; the type 22 operating in the usual well-known manner. In stenciling addresses or writing on cards, or similar work, the wear on the platen is centered in a rather small area. The present invention, however, permits the position of the holder to be readily changed, so that the wear may be more evenly distributed. The 100 position of the holder is changed by simply 105 110

drawing the locking bar 10 to the left, thereby loosening the holder, and then giving the latter a slight turn and returning the locking bar. A new surface or printing area 5 is thus presented to the type. The holder is also adapted for adjustment longitudinally of the platen. The holder may also be quickly removed entirely from the platen by spreading the two members on the hinge 10 9, and withdrawing the holder in a direction perpendicular to the platen axle.

Variations may be resorted to within the scope of the invention, and portions of the improvements may be used without others.

15 Having thus described my invention, I claim:

1. An attachment for the platen of a typewriting machine comprising a pair of hinged members adapted to surround the 20 platen, means to secure said members on the platen, and guides to receive and hold a card or work-sheet.

2. A card holder forming an attachment for the platen of a typewriting machine and 25 comprising hinged members adapted to surround the platen, and means for clamping the holder to the platen.

3. A holder forming an attachment for the platen of a typewriting machine, said 30 holder comprising members connected by a hinge extending longitudinally of the platen, and a clamping device connecting the free ends of said members and causing the holder to grip the platen.

35 4. A card holder forming an attachment for a platen and adapted to surround the platen, said holder having free edges adapted to be separated to permit the holder to be placed upon or removed from the platen, 40 and a clamping device to connect said free edges and draw the holder into clamping engagement with the platen.

5. A card holder attachment for a typewriter platen adapted to surround the 45 platen and having free edges extending longitudinally of the platen, a clamping device comprising a locking bar having a sliding connection with one of said edges, and locking pins on said bar, the other of said edges 50 being formed with cam slots to engage said pins.

6. A card holder attachment for the platen of a typewriting machine adapted to surround the platen and having free edges 55 adapted to overlap, and means forming a slot-and-pin connection between said edges for gripping the holder on the platen.

7. A card holder attachment for a typewriter platen adapted to surround the 60 platen and having free edges extending along the platen, and clamping means comprising a cam slot-and-pin connection between said edges, a relative movement of the slots and pins in one direction serving 65 to clamp the holder on the platen.

8. A card holder attachment for a typewriter platen adapted to surround the platen, a clamping device comprising a locking bar having a sliding connection with a free edge of said holder, the other free edge 70 of the holder being formed with cam slots, and pins on said locking bar adapted to enter said slots; said bar being movable longitudinally of the platen to draw the ends of the holder together and grip the holder on 75 the platen.

9. A card holder attachment for a platen comprising members connected by a hinge extending longitudinally of the platen, the free edge of one of said members being bent 80 back upon itself to form a socket or guideway, a clamping device comprising a locking bar slideable in said socket, and locking pins carried by said bar, the other hinged member having slots therein inclined to the 85 direction of said edge and adapted to receive said locking pins.

10. The combination of a typewriter platen, a card holder surrounding the same, and clamping means for gripping the holder to the platen and adapted to release said holder to permit the latter to be adjusted to different positions on the platen.

11. An attachment for a typewriter platen comprising hinged members adapted 95 to form a substantially cylindrical card holder surrounding the platen, said members being adapted to swing on their hinges and permit the removal of the holder in a direction perpendicular to the platen axle, 100 and means for clamping said holder on the platen.

12. An attachment for a typewriter platen comprising members connected by a hinge extending longitudinally of the 105 platen, said members surrounding the platen and having means to connect their free edges, and arc-shaped guides offset from the body of the holder and forming guideways to receive the edges of a work-sheet or card; the body of the holder being cut-away to expose the platen beneath the work-sheet and said hinge being positioned to form a stop for the leading edge of the card.

13. An attachment for a typewriter platen comprising members connected by a hinge extending longitudinally of the platen, said members surrounding the platen and having means to connect their free 120 edges, and arc-shaped guides offset from the body of the holder and forming guideways to receive the edges of a work-sheet or card.

14. A card - holding attachment for the revolute platen of a typewriting machine, 125 comprising a frame conforming to the curvature of the platen and having means to hold the opposite side edges of the card, a keeper or clasp hinged to said frame, the axis of the hinge extending longitudinally 130

- of the platen, said keeper or clasp also conforming to the curvature of the platen, and means causing the keeper and frame to grip the platen on opposite sides, said card holder being of such form that the feed rolls of the typewriting machine pass readily thereover.
15. A card - holding attachment for the revoluble platen of a typewriting machine, comprising a frame conforming to the curvature of the platen and having means to hold the opposite side edges of the card, a keeper or clasp hinged to said frame, the hinge extending longitudinally of the platen and forming a stop for the leading edge of the card, said keeper or clasp also conforming to the curvature of the platen, and means to cause the keeper and frame to grip the platen on opposite sides, said card holder being of such form that the feed rolls of the typewriting machine pass readily thereover.
20. A work-piece holding attachment for the revoluble platen of a typewriting machine, comprising a frame conforming to the curvature of the platen and adapted to hold a work-piece to the platen, the character of said frame being such that the platen printing field therefor is covered only by the work-piece supported thereby, a keeper or clasp connected to said frame and also conforming to the curvature of the platen, and means causing the keeper and frame to grip the platen on opposite sides, said work-piece holder being of such form that the feed rolls of the typewriting machine pass readily thereover.
25. A work-piece holder removably surrounding a platen to rotate therewith, and exposing within its borders the printing field on the platen which it serves, said holder inclosing said field on all sides, and work-holding means at the opposite sides of said field and distinct from said holder, to enable the placing and removal of work-pieces while the holder remains in said position.
30. A work-piece holder for the revoluble platen of a typewriting machine, comprising a frame removably encircling said platen to rotate therewith and having portions to grip said platen, said frame exposing that portion of the platen surface forming the printing field for a work-piece carried by said frame, and means on said frame distinct from said platen-gripping portions, to hold a work-piece and separated from the platen to permit the attachment and removal of the work-piece without disturbing the frame.
35. A work-piece holder for the revoluble platen of a typewriting machine, comprising a frame removably encircling said platen to rotate therewith and having portions to grip said platen, and exposing a limited printing field on said platen, and additional means on said frame separated from the

platen and distinct from said platen-gripping portions, to support a work-piece over said printing field.

20. A work-piece holder for the revoluble platen of a typewriting machine, comprising a frame removably encircling said platen to rotate therewith and inclosing on all sides a limited printing field on said platen, and means on said frame and distinct therefrom, and out of contact with the platen, to support a work-piece over said printing field.

21. A work-piece holder for the revoluble platen of a typewriting machine, comprising a frame removably encircling said platen to rotate therewith and bounding on all sides a limited printing field on said platen, and guides on said frame on the opposite sides of said field and distinct from said frame, to receive a work-piece and support it over said printing field in fixed relation to the platen and said frame.

22. A work-sheet holding attachment for a roller platen arranged to extend around the platen a sufficient distance to be held thereon without additional means externally of the holder, and means to draw the opposing edges of the attachment inwardly to cause the attachment to grip the platen to prevent movement of the attachment relatively to the platen, said means operable to release the attachment and permit adjustment thereof on the platen.

23. A work-sheet holder forming an attachment for a revoluble platen, and self-contained means comprised in said holder for clamping it to the platen with sufficient holding power to prevent movement thereof relatively to the platen, said means releasable to permit adjustment of the holder on the platen.

24. A card - holding attachment for the revoluble platen of a typewriting machine, comprising a card-holding frame conforming to the curvature of the platen and provided with curved guides for the lateral edges of a card, and a keeper hinged to said frame and extending on the opposite side of the platen from said holder, said keeper movable on its hinge into position to permit the removal of the card holder from the platen bodily in a direction perpendicular to the platen axis.

25. A card - holding attachment for the revoluble platen of a typewriting machine, comprising a card-holding frame having means to hold a card against the surface of the platen, a keeper hinged to said frame and arranged to engage the platen on the side opposite said frame, and clamping means to draw the free edges of said frame and keeper inwardly to clamp the attachment to the platen.

26. A card-holding attachment for the revoluble platen of a typewriting machine,

- comprising a card-holding frame having means to hold a card against the surface of the platen, a keeper hinged to said frame and arranged to engage the platen on the side opposite said frame, and clamping means to draw the free edges of said frame and keeper inwardly to clamp the attachment to the platen, said clamping means comprising a locking piece slidably mounted on one of said parts for movement longitudinally thereon, the other of said parts formed with cam surfaces operated by said locking piece to draw the said frame and keeper into clamping position. 10
- 15 27. An attachment for the platen of a typewriting machine comprising a card-holder and a clasp pivoted thereto in a manner to extend all around the platen and grip the same.
- 20 28. A circumferential card-holding device to surround a rotary platen of a typewriting machine, and comprising clamping means to contract said device into gripping engagement with the platen, said means releasable to permit removal of the device from the platen.
- 25 29. An attachment for a cylindrical platen comprising a card-holder and a pivoted clasp arranged to extend circumferentially of the platen, and means movable relatively to the card-holder and clasp, to draw the card-holder and clasp inwardly to grip the platen.
- 30 30. A card-holding attachment for a cylindrical platen arranged to extend circumferentially of the platen, comprising clamping means to cause the attachment to grip the platen circumferentially, said clamping
- means releasable to permit adjustment of the attachment on the platen. 40
- 35 31. A card-holding attachment for a cylindrical platen arranged to extend circumferentially of the platen and having free edges which may be separated a distance equal to the diameter of the platen to permit the attachment to be placed on the platen or removed therefrom in a direction transverse to the platen axis, and clamping means to draw said edges in a direction to cause the attachment to grip the platen. 45
- 40 32. A card-holding attachment for a cylindrical platen arranged to extend circumferentially of the platen and having free edges which may be separated a distance equal to the diameter of the platen to permit the attachment to be placed on the platen or removed therefrom in a direction transverse to the platen axis, and a clamping bar connecting said free edges and operable when moved in one direction to cause the attachment to grip the platen, and when moved in the reverse direction to free the attachment so that it may be adjusted relatively to the platen. 50
- 45 33. A card-holder attachment for a typewriter platen, arranged to surround the platen and having free edges extending lengthwise of the platen, and a clamping device to connect said free edges and draw the latter into clamping engagement with the platen. 55
- 50 60
- 55 65
- 60 70
- 65 70
